(57) **CLAIM**

The ornamental design for an atomizing core for electronic cigarette, as shown and described.

DESCRIPTION

FIG. 1 is a front perspective view of an atomizing core for electronic cigarette, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the atomizing core for electronic cigarette, which form no part of the claimed design.

All unshaded surfaces between solid and broken lines in FIG. 7 form no part thereof.
